UNITED STATES PATENT OFFICE.

AUGUSTUS C. CAREY, OF MALDEN, ASSIGNOR TO ALBERT A. POPE, OF BOSTON, MASSACHUSETTS.

IMPROVEMENT IN SPRING AIR-PISTOLS.

Specification forming part of Letters Patent No. 178,233, dated June 6, 1876; application filed February 16, 1876.

To all whom it may concern:

Be it known that I, AUGUSTUS C. CAREY, of Malden, Middlesex county, Massachusetts, have invented certain Improvements in Air-Pistols, of which the following is a specification:

The drawings accompanying this specification represent, in Figure 1, a vertical and longitudinal section of an air-pistol embodying my improvements, while Fig. 2 is a perspective view, and Fig. 3 a plan, of the adjacent ends of the barrel and air-magazine, the former showing the barrel as turned to one side or exposed to receive a projectile. Fig. 4, in said drawings, is a perspective view of the adjacent ends of the barrel and air-chamber, showing a modification of my improvements. Fig. 5 is a view of a stirrup-rod to be explained.

In these drawings, A represents the frame or stock of the pistol, consisting of a straight cylinder whose interior, B, constitutes the air-magazine or chamber. Within this air-chamber B is disposed a spring-impelled plunger, C, to which is attached a rod, D, that passes rearward through the cap E which closes the rear end of said chamber, the rod D serving to cock or set the plunger against the stress of its spring, and against or in rear of a spring-latch, attached to the under side of the stock, such latch constituting part of the lock of the pistol.

The above elements are shown in other applications for patents which I have filed simultaneously with this, and contain nothing, *per se*, which I now claim.

My present improvement relates to the peculiar method of attaching the barrel to the stock to convert the pistol into a breech-loading one; and consists in pivoting such barrel at its rear end to the front end of the air-magazine to one side of the common axes of the two, in such manner that by turning or partially rotating the barrel upon its pivot its bore is exposed and the projectile readily inserted.

My present improvements further embrace the employment, in connection with the plunger, of a rod or strap bearing at bottom a stirrup in which to place the user's foot, and

provided at the other end with a hook or other means of seizing hold of the rear end of the plunger-rod, in order that ample power may be obtained to overcome the stress of the plunger-spring in cocking such plunger.

The drawings accompanying this specification represent the barrel at G as secured at its rear end to an annular disk or hub, H, which is pivoted at its lower part to the front end of the air-magazine B, and eccentrically with respect to the bore of the latter and of the barrel.

When the barrel is in a closed or firing position its bore a is in alignment with, and constitutes, with a reduced diameter, a continuation of the bore of the air-chamber, and the contiguous faces of the hub H and air-magazine B are disposed obliquely to the axes of the two, in order that when the barrel is returned from an open to a closed position the parts shall crowd against each other and effect an air-tight joint.

A modification of this adaptation of the barrel would be, as shown in Fig. 4 of the drawings, to add to the front of the air magazine or cylinder A a lower branch or support, b, whose outer end is tubular, as shown at c, to receive and support in part the barrel G, which slides within it, the depression or space f intervening between the tubular support b and air-magazine permitting of the introduction of the projectile in the barrel when the latter is pulled forward.

The rear end of the barrel is let into a corresponding countersink in the air-magazine to obtain a close joint, and I prefer to add to the top of the barrel a pointed stop or guide, g, which enters a corresponding notch, d, in the cylinder A, and determines the proper position of the barrel. One of the screws e which confine the guide g to the barrel serves to determine the distance to which such barrel shall be pulled forward in the act of loading.

In this modification the barrel is pulled outward until the screw or stop e abuts against the tubular support, which opens or exposes the rear end of such barrel. The projectile is now inserted in this open end of the barrel, and the latter returned to place.

H', in the accompanying drawings, repre-

sents a rod or strap, or equivalent object, provided at one end with a hook, g' , to enter an eye, h , in the rear end of the plunger-rod D , or otherwise adapted to seize hold of such rod, and at its other end provided with a stirrup or handle, i , in which the user's foot may be placed to obtain great power over the stress of the plunger-spring, and relieve the hand of the user of the labor of contracting such spring in cocking or setting the plunger.

I claim—

1. In an air-spring pistol, the air-chamber

or cylinder, in combination with the barrel eccentrically pivoted to the front of the cylinder, and, when in firing position, communicating at its rear with an air-passage leading from the cylinder, as shown and set forth.

2. The rod H' , or its equivalent, in combination with the plunger C and its rod D , substantially as and for purposes stated.

AUGUSTUS C. CAREY.
